UNITED STATES PATENT OFFICE.

BYRON BARTHOLOMEW, OF JOLIET, ILLINOIS.

LOCKING SYSTEM.

1,379,610.

Specification of Letters Patent. Patented May 31, 1921.

Application filed May 5, 1919. Serial No. 294,735.

To all whom it may concern:

Be it known that I, BYRON BARTHOLOMEW, a citizen of the United States, and resident of Joliet, county of Will, and State of Illinois, have invented certain new and useful Improvements in Locking Systems, of which the following is a specification, and which are illustrated in the accompanying drawings, forming a part thereof.

10 The invention relates to a locking system, and has been developed with special reference to a locking system for jails.

An object of the invention is the provision of a jail wherein each of the cells may be locked from a central station. A further object is the provision of a jail wherein each of the cells may be locked from a central station, from which station the interior of each cell may be seen. A further object is 20 the provision of a jail in which the cells may be locked individually or simultaneously in selected groups from a central station. A further object is the provision of a locking system for jails wherein each cell may be 25 locked from a central station or by a key applied at the cell itself, if preferred.

A further object is the provision of a system by which the cells may be locked from a central station either singly or in multiple 30 by power-operated means. A further object is the provision of a locking system in which the cells may be locked from a central station, and wherein the improper actuation of any lock will be indicated at said 35 central station.

Further objects and the features of the invention will appear from the description when read in connection with the accompanying drawings forming a part of the 40 specification, wherein—

Figure 1 is a vertical section through the jail as a whole;

Fig. 2 is a plan view, partly broken away, of the jail structure;

45 Fig. 3 is a face view, broken away in portions, of the central station controlling means for the locks;

Fig. 4 is a vertical section on line 4—4 of Fig. 3, showing portions of the sleeves on one 50 rod 37 in section and a detachable lever in position;

Fig. 5 is a front view of a cell door and

casing with portions broken away to show the locking mechanism;

Fig. 6 is a transverse section taken on the 55 line 6—6 of Fig. 7;

Fig. 7 is a side view on an enlarged scale of the key locking mechanism;

Fig. 8 is a detail section looking both ways 60 from the line 8—8 of Fig. 3, and showing circuits for controlling the motors;

Fig. 9 is a plan view of a motor and the driving shafts for the lock actuation mechanism;

Fig. 10 is a cross-section on an enlarged 65 scale, taken on line 10—10 of Fig. 7, portions of the lock being omitted;

Fig. 11 is a side view of the bolt-operating mechanism; and

Fig. 12 is a detail perspective view of a 70 portion of the lock mechanism. The jail building as a whole is shown at 15. As illustrated in Figs. 1 and 2, the cells 16 of the jail are arranged about the exterior of a building shown as circular, but which may equally well be polygonal, and are arranged as shown in four tiers. Access to the balconies 17, from which the cells are entered, is had by means of the staircase 18, arranged 75 at the side of and over the entrance doorway 19. The central station occupied by the guards, and from which the locks are controlled, may preferably be entered by a subway, indicated in dotted lines on Fig. 2 of the drawings by reference 80 character 20. The floor 22 of the guardroom is reached by means of a ladder (not shown) and a central opening 21. In this guardroom there is a table 23, spaced away 85 from the walls 24 thereof, and it is upon and within the structure of this table that my central lock-controlling means are disposed.

The door of each cell is made to slide, as shown in Fig. 5, in which the door 25 is shown as sliding upon rollers 26 and as bearing upon its edge catches 27. These catches are adapted to pass through slots 28 in the door jamb 30, to be locked by means of the jump bar 29, sliding into the catches. The jump bar 29 is shown in Fig. 6 as bearing 95 two projections 31 and 32, either of which is adapted to cause movements of the jump bar, the former by means of a key and the 100

latter by means of power transmitted from the central station.

The power from the central station is applied through jump bar operating rods 33. 5 To cause movement of these rods a system of bodily movable mechanical means radiating from the central station is provided. As shown in Fig. 1 this system consists of bell-crank 34 and 35, connecting rod 36, and 10 main rod 37, leading downward from the guard station. The system mentioned, with rods 33 and the means for actuation described below, thus constitute means for distant control and actuation of the cell locks. 15 The mechanism for controlling the motions of main rods 37 is illustrated in Figs. 3 and 4. Movement upward of rod 37 is, by means of the bell-crank and connection, transmitted into movement downward of the 20 jump bar operating rods 33 and therefore causes the jump bar to enter the catches 27 and lock the cells. Each rod 37 is shown in Figs. 3 and 4 as bearing three sleeves 38, 44 and 46. Sleeve 38, which will be called the 25 rod sleeve, partakes of all vertical movements of the rod but may be rotated upon the rod to a limited extent because of its connection to the rod by means of the pin 39, fixed in the rod projecting into the circumferential 30 slot 40 in the sleeve. Near the lower end of the sleeve 38 there is an annular shoulder, shown more clearly in Fig. 4, at 41, and above this shoulder a pin 42 (Fig. 3) projects from this sleeve. Downward movement 35 of the rod sleeve, and therefore the rod, is caused by pressure upon the shoulder 41, and applied, by means of shoulder or collar 43, upon the sleeve 44, which will be called the intermediate sleeve, which in turn is pressed 40 upon by shoulder or collar 45 upon sleeve 46, which sleeve will be referred to as the power sleeve.

Movements upward of rod sleeve 38 will be caused by pressure against pin 42 applied 45 by means of the upper shoulder or collar 47 upon the intermediate sleeve 44, which in turn is pressed upward by pressure of spring 48, which pressure is applied by means of the shoulder or collar 49 upon the upper end 50 of the power sleeve 46. Thus, pressure downward upon the rod will be positive at this point, but pressure upward, which it will be remembered is the direction of motion when the cell is to be locked, is applied through the 55 spring 48, and is therefore a yielding pressure.

The lower end of the rod 37 slides in an eye 52, formed on the horizontal arm of the bell-crank 35, and actuates the crank through 60 the medium of a helical spring 50, sleeved upon the rod and interposed between the eye 52 and a collar 51 on the rod. Therefore, when the bell-crank, through any defect in operation, resists the pressure of the spring

50 sufficiently to allow compression of the 65 spring, the lower end of the main rod, which, as shown, is provided with a T head 53, may continue to move downward without injury to the mechanism.

Power is applied to the power sleeve 46 70 through sleeve lug 54 and connections, which will be described hereafter. To preserve the rotational alignment of intermediate sleeve 44 with the other two sleeves, the power sleeve is provided with an instanding pin 55, 75 which plays within a longitudinal slot 56 in the intermediate sleeve. When the rod sleeve 38 is rotated about the rod so that pin 42 registers with slot 56, upward motion of the power sleeve 46, transmitting motion to 80 intermediate sleeve 44, will fail to affect the rod sleeve and the main rod. Therefore, when in operating any group of main rods simultaneously by the power-operating means it is desired to leave one of the group 85 unaffected, the rod sleeve of that rod may be rotated until pin 42 comes into alignment with the slot as described. When this operation is carried out this main rod would then drop and unlock the corresponding cell, if 90 not prevented from doing so. To keep control of such rod there is shown a latch 57, pivoted upon a plate 58, which plate is made adjustable upon the covering plate 59 of the 95 table 23 upon which the rods are mounted. This latch 57 is pressed toward the rod by means of spring 60, and the adjustable plate 58 is provided that the latch may be adjusted so as to register with and engage one of a series of slots 61 provided on the rod sleeve. 100 When the rod is turned the slot 61 will catch upon the latch 57 and therefore keep control of the rod.

Preferably the locks are controlled in groups or in multiple, each group comprising one-half of the cells upon each floor. The four rods, shown in Fig. 3, are designed to be connected to the four cells arranged vertically in a tier, one on each gallery. To this end the power-operating means is connected to every fourth one of these rods, and by means of four motors 62, each cell upon each floor of one-half of the jail will be controlled. To connect the sleeve lugs 54 with the power there are shown bars 63, one 105 for each panel operated by each motor. These bars are connected to the sleeve lug through the intermediary of connectors 64. These connectors are necessary, since for purposes of uniformity I desire to have 110 the sleeves upon the main rods arranged at a uniform height and the bars 63 must be vertically spaced. Therefore one of the sets of sleeve lugs will be connected to its corresponding bar 63 by a relatively short connector, and other sleeves by successively longer connectors, as indicated in Fig. 3. Vertical motion is given bars 63 by means of 115 120 125

screws 65 revolved through worm gear mechanism 66, operated by means of motors 62.

Since the table 23, upon which the locking mechanism is placed, is polygonal and I desire to operate rods on more than one side of the table by a single set of motors, I have devised the arrangement shown in Fig. 9, in which are shown operating shafts 85. To transmit the motion of the shafts 85 around the corners I have provided universal joints 86, and I prefer to provide each shaft 85 with two sets of worm gearing 66, whereby each end of each bar 63 upon each panel of the table will be simultaneously operated.

It may be desirable to operate any individual cell from the central station manually. To this end I have provided means for attachment of a detachable lever 87, illustrated in Fig. 4. This lever is in the nature of a toggle, and one end of the toggle will be applied to a stud 88 upon the upper shoulder of the intermediate sleeve, and the other end to stud 89 upon the rod sleeve. When the rod sleeve is rotated by pulling on the handle of the lever so as to bring pin 42 in line with slot 56, and latch 57 is entered into lower slot 61, by pressing down upon the end of the lever 87 the weight will be taken off from latch 57, which may be withdrawn from the slot by hand. Then by pushing the rod down under the control of the detachable lever, the cell may be unlocked and the rod may be retained in any adjusted position by means of the various slots 61, illustrated in connection with latch 57. While this manual operation of any rod is going forward, or while the rod is in any adjusted position as referred to, the intermediate and power sleeves of that rod are free to move in unison with the other sleeves of their group, in response to operation of its motor, by coaction of slot 56 and pin 42. In the event that any lock becomes jammed or fails to work properly, the only result will be extra pressure placed upon spring 48. In the event that a cell door is not closed jump bar 29 will not enter the recess in catch 27, and will continue to lower during the entire motion of the power sleeve. This excess movement of the jump bar will be evidenced at the central station by the corresponding rod 37 rising above the remainder of the rods, and will therefore serve as an index to show that the cell in question is not properly locked.

For an adjustment of lengths of the main rods I have illustrated turn buckles 91, shown in Fig. 3. The upper ends of the rods are shown square so as to be more readily guided in frame member 92, and each rod is illustrated as bearing a projection 93 at right angles to its upper extreme, which pro-

jection is perforated. I have shown a cut-out switch at 82 which, in its open position, by means of a perforation through its end 95, may be locked to projection 93 by means of lock 94. When the switch 82 is locked to bar 37, as described, the bar 37 cannot be moved, nor can the group of which it is a member be operated in multiple by power from its motor 62.

The cell door 25, in Fig. 5, has a bar 96 projecting from one side of the top thereof, and such bar is provided with ratchet teeth 97. Pawl 98 is pivoted above this bar and is pressed toward the bar by means of spring 99.

Projection 125 extends from pawl 98 into the path of movement of T-head 126 on jump bar 29. When the jump bar is at the upper limit of its movement the T-head will, by lifting projection 125, hold the pawl out of contact with the ratchet teeth and the door will be free to open. When the jump bar is raised to a position wherein the same will just clear catches 27, the T-head will not contact with projection 125 and the door may be closed freely but cannot be moved in an opening direction because of the pawl and ratchet. This middle position is the position to which the jump bars are moved when the prisoners are to go into their cells. As each prisoner goes into his cell he is required to close his own door after him. With the jump bars in the middle position he will be unable to open the door again, whether he completely closes the same or not. Failure to completely close the door to bring the catches 28 into position for engagement with the jump bar when the same is lowered will be indicated at the central station by undue motion of the main rod, as explained above.

The central station control of jump bar 29 is through projection 32 and jump bar operating rod 33, as already described. The connection between these two parts is by means of a sliding bolt 100, Fig. 6. This bolt slides in the hollow slotted end of projection 32, and is provided with a pin 101 controlling its movement and rigid with the bolt. When rod 33 and projection 32 travel vertically as a unit, pin 101 travels therewith in slot 102 in the T-head of a bar 103, shown in detail in Fig. 11. This bar is shown as mounted to slide horizontally in guides 123 and a strap 124 over the free end thereof. Therefore sliding movement of bar 103 will shoot bolt 100 by pressing upon pin 101 so as to withdraw the same from or engage the same with the opening in bar 33 and thereby connect or disconnect the central operating mechanism with the jump bar.

Key-operated means for actuating the lock of each cell individually may be employed. This key-actuated means comprises a rotatable member 104, having a key-receiving

slot or opening and having gear teeth on its edge, and a sleeve 105 caused to rotate by co-action of gear teeth 106 with the gear teeth upon member 104.

5. Sleeve 105, freely rotating on stub shaft 105', carries four elements, viz:—first, a single toothed member 107 located near the back part of the compartment in which the lock is placed, the function of which is to shoot the 10 bolt 103 by coaction of its tooth with depression 108 therein.

The second instrumentality upon the sleeve 105 is a cam member 109. The function of this cam is to operate the toggle arms 110 15 and 111. These arms are spring-pressed toward the left as by spring 148, as seen in Fig. 7, and have a spring as 149 at the joint causing the same to tend to straighten, whereby the end of the arm 111 is retained 20 in contact with roller 112. Rotation of the lock in the direction of the arrow will, by causing the cam 109 to press upon pin 113, act to force the joint of the toggle to the right and the end of arm 111 upward into 25 contact with lug 114 upon the jump bar operating rod 33. The motion of the toggle after contact with the lug is merely sufficient to take the pressure of jump bar operating rod 33 off from pin 100, so as to allow the shooting 30 of bolt 100 out of connection with rod 33, and by the bearing of pin 113 against the outside of the cam during its continued rotation the pressure of rod 33 will be continuously supported.

35. The third element mounted upon sleeve 105 is wheel 115, bearing the gear teeth 106 already referred to.

The fourth element is the segmental gear 116. The function of this segmental gear is, 40 by coaction with rack teeth 117 upon projection 31, to raise the jump bar 29 and thereby free it from the catches 27.

The operation of the mechanism just described is as follows:—The initial movement 45 of the sleeve 105 will cause the motion of pin 113 to the right, bringing the end of arm 111 in contact with lug 114 and lifting rod 33 slightly before tooth 107 comes into register with depression 108. Tooth 107 will 50 coact with depression 108 so as to withdraw bolt 100 from rod 33 before segmental gearing 116 takes into rack teeth 117. Therefore, when the segment and rack teeth come 55 into action there will be nothing to prevent the action of a key, not shown, applied to key hole 151 from lifting the jump bar 29. Toggle arms 110 and 111 are pivoted to a projection 118, shown in Fig. 6, to space the same away from the back of the lock cavity 60 a proper distance.

The lock cavity is shown as being applied opposite pier 119, which forms a partition between adjacent cells, and the cavity is formed by the projection of jambs 30 be-

yond the pier and a covering plate 120 connecting the jambs. The rods 33 run vertically from one story to another within these cavities, and are shown as offset at 121 (Fig. 5), to bring them into alignment with the lock which they are to actuate. The doors 70 25 may be provided with glass, preferably wire glass, at 122.

The control means for motors 62 are indicated in Fig. 3, and the construction is more clearly shown in Fig. 8. The view of 75 Fig. 8 is, as described, a section looking in both directions from line 8—8 of Fig. 3. However, in Fig. 8 the upper end or extension 67 is shown in full lines but in different 80 positions in each half. As shown in Figs. 3 and 4, a casing is placed over the end of extension 67 and rests on table 92. This casing contains the control mechanism, and projecting from it are push buttons 69, 70, 71 and 72 pressed outwardly by springs 73. 85

The structure of the circuit-closing mechanism operated by the push buttons is clearly illustrated in Fig. 8, where sliding plate 74 is shown as guided in ways 75. L-shaped detent 76 is pivoted to plate 74, 90 as at 77, and is spring-pressed against stop 78 by spring 79 when not prevented by contact of the short arm of the detent with projection 80, which projection is rigidly secured to the casing. Each sliding plate also 95 carries two circuit-closing elements, as 81, 82, coacting with contacts 83 and 84. Extension 67 of connector 64 carries lugs which project so that their path of movement will bring them into engagement with an L-shaped arm on the corresponding side of the extension if the same have its push buttons depressed.

The normal position of the circuit closer with the circuit open is shown at the left 105 and upper right of Fig. 8. From this position if the button be pressed against resistance of spring 73 to the position of the lower right portion of Fig. 8, detent 76 will be removed from projection 80, and by influence of spring 79 will be pressed against stop 78. Pressure being removed from the push button the end of the short arm of the detent lying against the end of projection 80 will hold the sliding plate in the advanced 110 position with end 129 in the path of movement of the corresponding lug 127 or 128.

With extension 67 in the position shown at the right of Fig. 8, the jump bar is down and the cells are locked. When button 72 is 120 pressed as shown in that figure a circuit will be closed as follows: from the source of energy through wire 129, armature 130, wires 131, 132, contacts 83 and 81, wire 135, 136, to the source of energy. There is also 125 a path from contact 81 through wires 137, 138, field windings 139, wires 140, 141, contacts 84 and 82, wires 142, 136, to the source

of energy. It will be noted that as described the current through the field flows also through the armature and hence the motors used are series wound.

- 5 The motors are connected in such a manner that the current just traced will cause the motor to move extension 67 downwardly and the jump bar upwardly until at the lowest desired position of the extension lug 10 127 will impinge upon end 129 of the detent, thus raising the short arm thereof out of its position against projection 80, when spring 73 will retract the mechanism, open the circuit and stop the motor.
- 15 If now button 69 be pressed a circuit will be closed as follows: wire 129, armature 130, wires 131, 143, 144, contacts 81, 83, wires 145, 136, to the source of energy. Also a circuit from contact 81 through wires 20 146, 140, to the field winding 139, wires 147, 148, contacts 84 and 82, wires 149, 129 to the source of energy. It will be seen that the circuit just traced passed in the same direction through the armature, but in the opposite 25 site direction through the field from the circuit closed by button 72, and hence the motor would be operated in the opposite direction.

- Since the contacts actuated by button 71 30 and 72 are wired in parallel, as are those actuated by buttons 69 and 70, buttons 69 and 70 will cause a motor to revolve in one direction and 71 and 72 in the opposite direction. Also the detents 76 and projection 80 35 for buttons 69 and 70 are inverted, as compared with those of 71 and 72, and hence will serve to stop the motor upon upward travel of extension 67 through action of lug 128, in the same manner as the mechanism 40 of buttons 71 and 72 will stop the motor on downward travel of the extension through action of lug 127.

- The normal routine of actuation of the mechanism would be; from full locked position with 67 at its highest point to full unlocked by use of button 72; from this position with the cell doors left open to middle position by use of button 70, (this places the ratchet mechanism of the doors in operative 45 position so that any door may be shut and caught, though not locked by the jump bar); and from this middle position to full locked by use of button 69.

- In the event that button 69 has been 50 operated while the cell doors are open for any reason, the middle position of the jump bar may be reached at once by use of button 71.

- In the claims I have referred to control 55 and actuation of the lock. By control I wish to be understood to refer to not only actuation but to the maintaining of the lock in any position to which it has been actuated. In other words, control is intended to 60 refer to causing movement or preventing

movement, while by actuation I wish to be understood as meaning the causing of movement of the locks to either lock or unlock the cells.

Also in the claims where the expression 70 "locking the cells" is used it is to be understood as referring to fastening the closure of any means of egress from or ingress to the cells whether the means be a door, window, port hole or any other opening. 75

I claim as my invention—

1. A prison comprising a plurality of cells, a central station from which the interior of each cell is visible, bodily movable mechanical means radiating from the central station and connecting with said cells for simultaneously locking a plurality of 80 said cells.

2. In combination, a plurality of cells, locking means for each cell, a central station, means at said central station for individual control of said locking means, means at said station for multiple control of said locking means, and means for retaining control of said locking means while changing 85 from individual to multiple control. 90

3. In combination, a lock, means for key actuation of said lock, means for actuating said lock from a distance, and means under control of said key-actuating means for automatically disconnecting said distant actuating means when said key is used to unlock the lock. 95

4. In combination, a lock, means for key actuation of said lock, means for actuating 100 said lock from a distance, means operated by said key actuating means for disconnecting said distant actuating means when unlocking and connecting said distant actuating means when locking said lock. 105

5. In combination, a lock, means for key control of said lock, means for distant control of said lock, and means operated by said key control means for disconnecting said distant control means without interfering 110 with movement of said distant control means while disconnected.

6. Means for operating a distant lock comprising a main rod mounted for reciprocation, a rotatable rod sleeve on said rod held 115 against longitudinal movement relative thereto, a power sleeve on said rod sleeve, means for applying power to said power sleeve for reciprocation thereof, and means whereby movement of said power sleeve will 120 reciprocate said rod sleeve while in one position and will not reciprocate said rod sleeve while in another position.

7. Means for operating a distant lock, comprising a main rod mounted for reciprocation, a rotatable rod sleeve held thereon against longitudinal movement relative thereto, and intermediate sleeve held against rotation mounted on said rod sleeve, a power 125 sleeve mounted on said intermediate sleeve, 130

- means for applying power to said power sleeve for its reciprocation, resilient means for causing said intermediate sleeve to move with said power sleeve, and means for transmitting movement of said intermediate sleeve to said rod sleeve inactive in a certain position of the rod sleeve.
8. Means for operating a distant lock comprising a main rod mounted for reciprocation, a power sleeve mounted thereon, means for applying power for reciprocation of said power sleeve, and resilient means for transmitting motion of said power sleeve to said main rod.
15. 9. Means for controlling a distant lock comprising a reciprocating rod, a rod sleeve rotatably mounted thereon but held against longitudinal movement relative thereto, a longitudinally slotted intermediate sleeve mounted on said rod sleeve, a collar at each end of said intermediate sleeve, a power sleeve on said intermediate sleeve, an inwardly projecting pin on said power sleeve projecting into said slot, a coiled spring about said intermediate sleeve abutting against its upper collar and the end of said power sleeve, a pin on said rod sleeve normally resting against said intermediate sleeve but when turned into register with said slot allowing independent reciprocation of said power and intermediate sleeves, and latch mechanism operable when said rod sleeve pin is in registry with said slot to control movement of said rod.
35. 10. Means for multiple control of a plurality of distant locks comprising a vertically reciprocable rod for each lock, an arm for reciprocation of each rod, a horizontal vertically movable bar connected with said arms, and means to actuate said bars.
11. In combination, a plurality of locks, individual means for distant control of each lock comprising a vertically reciprocable rod at the control point, an arm connected with each rod for its actuation, a plurality of horizontal bars, each bar connected with a group of said arms, and means for actuating said bars.
45. 12. In combination, a plurality of locks, means at a distant point for multiple control of said locks comprising a bar, a motor for actuating said bar, a projection moving with said bar, a switch controlling the circuit to said motor, and means carried by said projection for automatically controlling said switch.
13. In combination, a plurality of locks, means at a distant point for multiple control of said locks comprising a bar, a motor for actuating said bar and locks, a projection moving with said bar, two circuit closing contacts, pole changing contacts, mechanism for controlling said contacts, a slidable stop normally in the path of movement of said projection when said contacts are closed and adapted to cause said contacts to open at the end of the desired travel of said bar.
14. In a locking system, in combination, a lock, a control station, means extending from said lock to said control station, means at said control station for actuating said lock through said first named means comprising a reciprocable member carrying a projection, an electric motor for actuating said member in either direction according to its direction of rotation, sets of circuit closing and pole changing contacts for causing said motor to operate in either direction, and a trigger associated with each set of circuit and pole changing contacts and standing in the path of movement of said projection when the contacts with which it is associated are closed to open the contacts and stop the motor at the desired limit of travel of the reciprocable member.
20. 15. In combination, a cell door having a catch, a jump bar coöperating with the catch and having a range of movement beyond the catch-engaging position, a power-actuated rod for actuating the jump bar and having a positive connection therewith, a power device, and cushioned connection between the power device and the rod.
25. 16. The combination with a cell door having a catch, a jump bar engageable with the catch, a reciprocating rod normally connected with the jump bar, a distant control station, means at such station for moving the reciprocating rod, and key-actuated means for disconnecting the jump bar from the rod and actuating such bar.
30. 17. A prison comprising a plurality of cells facing substantially toward a common center, a central station located at said center, means at said station for simultaneously locking and unlocking a plurality of said cells, and means at said station for preventing the locking or unlocking of chosen individual cells by said first named means.
35. 18. A prison comprising a plurality of cells facing substantially toward a common center, a central station located at said center, bodily movable mechanical means radiating from said station and extending to said cells for locking and unlocking the same and means at said station for actuating said mechanical means to simultaneously lock or unlock a plurality of said cells.
40. 19. A prison comprising a plurality of cells facing substantially toward a common center, a central station located at said center, bodily movable mechanical means radiating from said station and extending to each individual cell, means at said station for acting upon said mechanical means to lock and unlock a plurality of said cells simultaneously.
45. 20. A prison comprising a plurality of cells facing substantially toward a common center, a central station located at said center,

ter, bodily movable mechanical means radiating from said station and extending to each individual cell, means at said station for acting upon said mechanical means to lock and unlock a plurality of said cells simultaneously and means to prevent said second named means from causing the locking or unlocking of chosen individual cells.

21. A prison comprising a plurality of cells facing substantially toward a common center, a central station located at said center, mechanical means extending from each individual cell to said station, means at said station for acting upon said mechanical means to lock and unlock a plurality of said cells simultaneously and means at said central station for acting on said mechanical means to individually lock and unlock selected cells.

22. A prison comprising a plurality of cells facing substantially toward a common center, a central station located at said center, a vertically reciprocable rod individual to each cell located adjacent the cell, adapted upon being reciprocated to lock and unlock the cell, a series of horizontal rods radiating from said central station, one end of each having bell crank connection with one end of each of the vertical rods and means at the central station to actuate the horizontal rods to reciprocate said vertical rods.

23. In combination, a door, means for locking said door in a fully closed position, mechanism for locking said door against opening movement when in any position, instrumentalities adjacent said door operable in a first position to render both said means and said mechanism operative, in a second position to render said mechanism operative and said means inoperative and in a third position to hold both said means and said mechanism inoperative and means for moving said instrumentalities to a selected one of said three positions.

24. In combination, a door, means for

locking said door in a fully closed position, mechanism for locking said door against opening movement when in any position, instrumentalities adjacent said door operable in a first position to render both said means 50 and said mechanism operative, in a second position to render said mechanism operative and said means inoperative and in a third position to hold both said means and said mechanism inoperative and means at a 55 central station for moving said instrumentalities to a selected one of said three positions:

25. A prison comprising a plurality of cells facing substantially toward a common 60 center, a central station located at said center, a vertically reciprocable rod adjacent to each cell adapted by its movement to lock the cell, a series of rods radiating from said central station each rod of said series 65 having actuating connection with one of said reciprocable rods, a series of vertically reciprocable rods at the central station one having actuating connection with each of said horizontal rods and means to actuate 70 said central station vertical rods individually or in multiple.

26. A prison comprising a plurality of cells facing substantially toward a common center, a central station located at said center, a vertically reciprocable rod adjacent to each cell adapted by its movement to lock the cell, a series of rods radiating from said central station each rod of said series having actuating connection with one of said reciprocable rods, a series of vertically reciprocable rods at the central station one having actuating connection with each of said horizontal rods, means to actuate said central station vertical rods individually or in 80 multiple, and key operable means at each cell adapted to render said first named reciprocable rod inoperative and to lock and unlock the cell by means of a key.

BYRON BARTHOLOMEW.
